UNITED STATES PATENT OFFICE.

AH LEON STANLEY YU, OF HONG KONG, CHINA.

WIREWORKING MACHINE.

Application filed January 26, 1923. Serial No. 615,158.

To all whom it may concern:

Be it known that I, AH LEON STANLEY YU, a citizen of China, and a resident of Hong Kong, China, have invented certain new and useful Improvements in Wireworking Machines, of which the following is a specification.

The present invention relates in general to wire working machines, and more particularly to an improved wire working machine especially adapted for use in the production of hat frames or the like.

The object of the invention is to provide an improved machine of this character which unites the elements of the hat frame positively and securely and eliminates the necessity of manually wrapping these elements with wire, which is rapid and certain in its operation, which is of simple and durable construction, reliable in operation, and easy and inexpensive to manufacture, and which has a wide range of utility.

Other objects and advantages of the invention reside in certain novel features of the construction, combination and arrangement of parts which will be hereinafter more fully described and particularly pointed out in the appended claims, reference being had to the accompanying drawings forming part of this specification, and in which:

Figure 1 is a perspective view, illustrating the preferred embodiment of the invention;

Figure 2 is a view in longitudinal section, parts being shown in elevation for the sake of illustration;

Figure 3 is a detail view in section, illustrating the working bit or wire holder and the stationary die;

Figure 4 is a perspective view of the working holder illustrating one phase of the operation of manufacturing the wire hat frame;

Figure 5 is a detail perspective view of the movable die;

Figure 6 is an end elevational view of the work table and stationary die;

Figure 7 is a view thereof in transverse section;

Figures 8 and 9 are fragmentary detail views of the stationary die, showing the formation of the inclined grooves of the die face thereof;

Figure 10 is a diagrammatic perspective

view, illustrating the first phase in the formation of a wire joint of a hat frame;

Figure 11 is a similar view, illustrating the second phase in the formation of the joint;

Figure 12 is a fragmentary plan view, illustrating the third and final phase in the formation of the joint;

Figure 13 is a fragmentary view, in side elevation also illustrating the third and final phase in the formation of the joint;

Figure 14 is a view, illustrating a somewhat different joint which may be produced by the present invention.

Referring to the drawings wherein for the sake of illustration is shown the preferred embodiment of the invention, the numeral 10 designates a central post, upon which the bed or work table for the wires designated generally at 12 is arranged. The bed or work table 12 includes a stock or sleeve 13 having a limited movement on the post 10 and a fixed section 14 secured by means of a screw or the like 15 to the central post 10 and having tongue and groove connection 16 with the main portion or section of the sleeve or stock.

The slideable sleeve 13 is urged outwardly on the post 10 to the position shown in Figures 1, 2 and 4 by means of a coil spring 18 arranged on the post and abutting the sleeve 13 at one end and a collar 19 at its other end. The collar 19 is fixed to the post 10.

The fixed section 14 of the stock or sleeve is slightly longer than the major portion 90 thereof and projects from one end of the sleeve to provide a head 21; the head 21 being formed with a transverse guide opening 21^a through which the crimping or tie wire is inserted. The head 21 also constitutes an element of the cutting means for the tie wire, as will hereinafter more fully appear. Diametrically opposite the head 21 a lug 22 is integrally formed with the stock or sleeve 14 and is adapted to engage the end of the tie wire inserted through the opening 21^a thereby serving as a stop or gauge for the tie wire. The end of the stock at which the head 21 and lug 22 are located and which is designated generally at 23 constitutes the 100 work table proper, and it is divided by the head 21 and lug 22 into sections 24 and 25.

The section 24 is provided with radial grooves 26 and 27 and the section 25 is provided with radial grooves 28 and 110

29 which are alined with the radial grooves 26 and 27, respectively, being directly opposite, so that the alined grooves are complementary to each other, and the 5 complementary grooves constitute seats or holders for the wires. The stock 13 is provided with radial ribs 30, 31, 32 and 33 extending from the stock below and in alinement with the grooves 26, 27, 28 and 29, respectively and having their top edges or surfaces coplanar with the bottoms of the grooves so that these ribs serve to enlarge the seats presented by the grooves and to afford a positive support for the wires for the 10 major portion of their extent within the stock.

It is to be noted that the radial ribs 30, 31, 32 and 33 extend only part of the way toward the center and leave a circular or 20 cylindrical space 38 in which the stationary die or anvil 40 is adapted to be arranged in the operation of the machine. The stationary die or anvil 40 is removably fitted in the end of the post 10, the screw 15 being 25 advantageously utilized for this purpose, as shown in Figure 3, although a separate screw or other releasable fastening means may be employed, if desired. The anvil die 40 is provided with a grooved die face 40^a 30 which operates upon the tie or crimping wire in a manner which will hereinafter be more fully described. It is to be understood of course that the stationary die does not move but the stock mounted on the base does 35 move so as to bring the stationary die within the space 38.

A movable die 41 is provided and includes bits 43 and 44 having notches or kerfs 45 and 46 therein which receive the portions of 40 the wire to be bent or shaped. The circumferential edge 43^a of the bit 43 also constitutes a cutter, being cooperable with the head 21 to sever the desired length of tie wire. The body of the movable die is slotted longitudinally to accommodate the ribs 30, 31, 32 and 33 as well as the wires carried thereby.

In the operation of the die as thus far described, the wires W and W' of the hat frame which are to be united or connected 50 are arranged on the seats constituted by the complementary notches and the alined ribs. The binding or tie wire T that is to be bent around the wires to be united is inserted through the opening 21^a of the fixed section 55 of the stock far enough to reach completely across the opening of the fixed die and until it touches part 22. One instance or illustration of wires so arranged is shown in Figure 4.

60 The movable die is then forcibly urged toward the stationary die. The first phase in the action which follows is the cutting of the requisite length of tie or binding wire T which is accomplished by the circumferential cutting edge 43^a of the bit 43 which

coacts with the head 21 for this purpose. After this first phase of the operation has been completed the wires are related as shown in Figure 10 that is with the wires W and W' crossing and the severed length 70 of the tie or binding wire overlying the crossing of the wires W and W'. While the cutting action is being carried out the bit 43 as well as the bit 44 is engaged with the tie wire and following the severance of the requisite length of the tie wire the severed length 75 is bent around the crossed wires W and W', this bending being carried out by the bits until the binding or tie wire assumes the U-shaped form shown in Figure 11. During the 80 severing of the requisite length of the tie wire and during the initial bending thereof, the movable section or sleeve 13 of the work table is held substantially stationary on the post 10 by the coil spring 18 and the movable die 85 moves inwardly of the sleeve 13, the longitudinal slots of the movable die accommodating the wires to be united and the ribs on which these wires are positively supported. When, however, the initial bending of 90 the tie wire has been completed, the inner end walls of the longitudinal grooves of the movable die 41 engage the portions of the wires which are positively supported on the ribs 31, 32, 33 whereby any subsequent movement of the movable die is transmitted to the sleeve 13 and the same is moved along the post 10 against the action of the coil spring 18 in order to permit the movable die 41 and the stationary die 40 to coact to 95 complete the bending of the tie wire as will now be described. At this time the ends of the binding wire are disposed immediately adjacent the curved or inclined walls of the 100 grooves of the die face of the stationary die 105 so that as the relative movement between the dies progresses these ends will be engaged by the inclined or curved walls of the 110 grooves of the die face and the binding wire will be bent around the wire W' as shown in Figures 9, 12 and 13, thus completing the joint.

A gage is organized with the machine and comprises a sliding frame 50 including parallel side bars 51 slidably mounted in guideways 52 provided in the collar 19 and held therein by means of a washer or the like 54 fixed to the post 10. A set screw 55 secures the sliding frame in adjusted position. One of the lateral faces of the sliding frame is provided with graduations 56 which provide for the accurate adjustment of the gage. The gage carries a bar 57 disposed at right angles to the sliding frame and having its upper end provided with a central slot 58 which receives one of the elements of the 115 hat frame.

In order to provide for the formation of the joint shown in Figure 14, the section 23 of the work table or bed of the stock 13 is 120 125 130

also provided with a groove 60 intermediate the grooves 26 and 27 and constituting a seat for the wire T'. In addition to the longitudinal groove in the movable die 5 which accommodate the ribs 30 to 33, inclusive, as well as the wires carried thereby, this movable die is also provided with a groove 61 which coacts with the groove 60 in the formation of the joint shown in Figure 14. As shown in this figure three wires W, W' and T', such as are found in the center of the top of a hat frame, are bound together. The third wire T' is itself looped over across the other two wires and functions as the tying or binding wire.

In forming this joint the wires W and W' are arranged on the seats constituted by the complementary notches and the alined ribs and the wire T' is received in the groove 60 and has its end extending over the crossing of the wires W and W' and just beyond the same. The movable die 41 is then brought in such angular relation with the stationary die that the groove 61 of the die 25 40 is alined with the groove 60 of the stock, the bits 43 and 44 being alined with the head 21 and lug 22 respectively, and thus being idle during the operation. The movable die 41 includes however a third bit or die face 30 designated at 63, which engages the end of the wire T' extending beyond the crossing of the wires W and W' and bends this projecting end of the wire T' down into engagement with the underlying groove of the die face 40^a whereby the wire T' is looped around the wires W and W' as shown in Figure 14.

I claim:

1. In a wire working machine, a post, a work table including a stock slidable on the post and having a section fixed to the post, said stock having a plurality of grooves constituting seats for the wires to be united and having ribs complementary to said grooves, 45 a head integral with the fixed section of said stock and having a transverse opening therein adapted to receive the binding wire, a coil spring arranged on the post and engageable with the stock, a stationary die carried by the post within the stock, a movable die having a pair of bits, one of said bits being cooperable with the head for severing the requisite length of the binding wire and both of said bits being engageable 50 with the severed length to partially bend the binding wire and to move it into engagement with the stationary die, said stationary die being adapted to complete the bending of the binding wire.

2. In a wire working machine, a post, a work table including a stock slidable on the post and having a section fixed to the post, said stock having a plurality of grooves constituting seats for the wires to be united

and having ribs complementary to said grooves, a head integral with the fixed section of said stock and having a transverse opening therein adapted to receive the binding wire, a lug carried by the stock and engageable with the end of the binding wire, a coil spring arranged on the post and engageable with the stock, a stationary die carried by the post within the stock, a movable die having a pair of bits, one of said bits being cooperable with the head for severing the requisite length of the binding wire and both of said bits being engageable with the severed length to partially bend the binding wire and to move it into engagement with the stationary die, said stationary die being adapted to complete the bending of the binding wire.

3. In a wire working machine, a work table having seats for the wires to be united and means for supporting the binding wire, a movable die having bits engageable with the binding wire for effecting initial bending thereof, and a stationary die having a die face provided with inclined grooves engageable with the ends of the binding wire after the initial bending operation and adapted to coact with the movable die to complete the bending of said binding wire.

4. In a wire working machine, a work table having seats for the wires to be united and means for supporting the binding wire, a movable die having bits engageable with the binding wire for effecting initial bending thereof, one of said bits having a cutting edge engageable with the binding wire for severing the desired length of the same prior to the bending of said wire by said bits, and a stationary die having a die face provided with inclined grooves engageable with the ends of the binding wire after the initial bending operation and adapted to complete the bending of said binding wire.

5. A wire working machine for use in securing wires by bending a tie wire there-around and comprising a yieldably mounted work table having slots for the wires to be united, a movable die adapted to initially bend the tie wire, and a stationary die cooperable with the movable die to complete the bending of the tie wire about the wires to be united.

6. A wire working machine comprising a post, a work table carried by the post, a stationary die carried by the post, a movable die cooperable with the work table and with the stationary die and a gage including a slidale frame carried by the post, and a bar carried by said frame and having a wire receiving slot therein.

7. A wire working machine for use in securing wires by bending a tie wire there-around and comprising a work table including a fixed section and a movable section,

means yieldably resisting movement of the movable section, the movable section having seats for the wires to be united, the fixed section having means for supporting the tie wire, a movable die cooperable with the fixed section for severing the requisite length of tie wire and adapted to initially bend the severed length about the wires to be united, and a stationary die cooperable with the movable die to complete the bending of the tie wire about the wires to be united.

8. A wire working machine for use in securing wires by bending a tie wire there-around and comprising a post, a work table comprising a stock mounted on the post and including a movable section slidably mounted on the post and a fixed section secured to the post, the fixed section limiting the movement of the movable section in one direction, a coil spring for resiliently resisting the movement of the movable section in the other direction, the movable section having seats for the wires to be united, the fixed section having means for supporting the tie wire, a movable die cooperable with the fixed section for severing the requisite length of tie wire and adapted to initially bend the severed length about the wires to be united, and a stationary die cooperable with the movable die to complete the bending of the tie wire about the wires to be united.

9. A wire working machine comprising a stock having slots and ribs complementary to said slots, said slots and said ribs forming a positive support or seat for the wires, a stationary die arranged within said work table and having a die face provided with inclined grooves and a movable die having longitudinal slots for accommodating said

ribs and the wires carried thereby and having bits constituting die faces.

10. A wire working machine for use in securing wires by bending a tie wire about the wires to be united and comprising a post, a work table yieldably mounted on said post and having seats upon which the wires to be united are positively supported, a movable die having a bit adapted to initially bend the tie wire, the movable die having slots accommodating the wires supported on the seats during the initial bending operation, the movable die being positively engaged with the wire supported on the seats after the initial bending has been completed to move the work table along said post and a stationary die carried by the post and cooperable with the movable die to complete the bending of the binding wire when the work table is moved along the post.

11. A wire working machine comprising a post, a stock slidable on said post, a coil spring for resisting sliding movement of said stock in one direction, a stationary die arranged within said stock and a movable die cooperable with said stationary die.

12. A wire working machine comprising a post, a stock slidable on said post and having a fixed section, said stock having a plurality of grooves constituting seats for the wires, said fixed section having means for supporting the binding wire, a stationary die within the stock and having a die face provided with inclined wire engaging grooves, and a movable die having bits engagable with the wires and cooperable with the stock and with the stationary die to effect bending of the wires.

AH LEON STANLEY YU.
